[57] CLAIM

The ornamental design for a jewelry presentation case,
as shown and described.

DESCRIPTION

FIG. 1 is a perspective view of a jewelry presentation
case, showing my new design;

FIG. 2 is a perspective view thereof, in open position;

FIG. 3 is a right-side elevational view thereof, the left-

side elevational view being a mirror image thereof;

FIG. 4 is a front elevational view thereof;

FIG. 5 is a rear elevational view thereof; and,

FIG. 6 is a top plan view thereof.

The bottom surface is plain and unornamented.

FIG. 1

FIG. 2

FIG. 3
